UNITED STATES PATENT OFFICE.

FRED J. HEIDEMAN, OF DETROIT, MICHIGAN, ASSIGNOR, BY DIRECT AND MESNE ASSIGNMENTS, TO HOUSEHOLD UTILITIES CORPORATION, OF DETROIT, MICHIGAN, A CORPORATION OF DELAWARE.

REFRIGERATING-TANK.

1,350,453.

Specification of Letters Patent. Patented Aug. 24, 1920.

Application filed April 16, 1919. Serial No. 290,545.

To all whom it may concern:

Be it known that I, FRED J. HEIDEMAN, a citizen of the United States, residing at Detroit, in the county of Wayne and State of Michigan, have invented a new and useful Refrigerating-Tank, of which the following is a specification.

This invention relates to refrigerators, and more particularly to such refrigerators as are cooled by circulation of a cooling medium within coils immersed in brine or some other liquid having a relatively low freezing point.

It is the object of the invention to insure a positive circulation of the brine or similar liquid so that within a comparatively short period of time all portions of said liquid will come either into contact or into proximity to the immersed coils and yield up their heat thereto, a more uniformly low temperature thus being maintained in the entire body of brine than is otherwise obtainable without increasing the number of cooling coils.

In attaining said object the invention contemplates providing a brine tank having the cooling coils which are immersed therein of such a shape as to secure a cooling effect that is unbalanced with respect to opposed sides of the tank, and having open air chambers therein one or more of which is eccentrically located so as to accentuate the unbalanced temperature conditions at the opposed sides of the tank by compelling an unbalanced absorption of heat from the air, a thermosiphon circulation of the brine being induced by the unbalanced temperature conditions.

A preferred embodiment of the invention is disclosed in the accompanying drawings, wherein,

Figure 1 is a perspective view of the improved refrigerator.

Fig. 2 is a vertical sectional view of the brine tank, the section being taken on line 2-2 of Fig. 3.

Fig. 3 is a vertical sectional view of said tank, the plane of section being parallel to the front wall of the tank.

In these views the reference character 1 designates a refrigerator, adapted to be cooled by mechanical refrigeration and having in one of its compartments the brine tank 2. Said tank is formed with upper and

lower open air passages 3 and 4 respectively, the lower of which is eccentrically located 55 so as to form at one side thereof a hollow column 5 of considerable thickness, while the hollow column 6 at the other side is comparatively thin. Within the upper portion of the tank 2 there is located the coil 7 60 through which the refrigerant is adapted to circulate, said coil surrounding the air passage 3 and being of an unsymmetrical shape so as to exercise an unbalanced cooling effect, the larger portion of the coil being positioned 65 above the relatively thick column 5.

In the operation of the above-described invention the upper portion of the brine tank is unbalanced as to temperature conditions because a relatively large portion of the coil 70 7 is positioned at one side of the vertical axis of the tank. Correspondingly unbalanced temperature conditions exist in the lower portion of the tank for the reason that there is a relatively large hollow column 75 5 beneath the larger portion of the coil 7, while the hollow column 6 below the smaller portion of the coil is of lesser thickness. The smaller column being more readily raised in temperature by the heat absorbed 80 from the air becomes warmer than the column 5. Because of the unbalanced temperature conditions thus created, there is a tendency for the brine to flow downwardly through the column 5 and upwardly through 85 the column 6, setting up the circulation indicated by the arrows in Fig. 2. Because of this circulation, the portion of the brine bathing the coils 7 is constantly changing and the heat of the air within the compartment receiving the tank is more rapidly 90 transferred to the brine and thence to said coils than where positive circulation is lacking.

While it is common in the present state of 95 the art to immerse the refrigerating coils within a brine tank having open air passages therein, it is believed to be an innovation to secure unbalanced temperature conditions and a consequent positive circulation 100 105 as has been described.

What I claim is:

1. The combination with a coil for circulation of a cooling medium, of a tank containing a liquid wherein said coil is immersed, said tank being formed with an air

passage eccentric to the vertical axis of the tank, whereby a thermo-siphon circulation is induced around said air passage.

2. The combination with a coil for circulation of a cooling medium, of a tank containing a liquid wherein said coil is immersed, said tank having upper and lower air passages, the upper air passage being surrounded by said coil and the lower air passage being eccentric to the vertical axis of the tank to induce a thermo-siphon circulation around said lower passage.

3. The combination with a coil for circulation of a cooling medium, of a tank containing a liquid wherein said coil is immersed, said coil having unequal portions at opposite sides of the vertical axis of the tank, producing an unbalanced cooling effect and a consequent thermo-siphon circulation.

4. The combination with a coil for circulation of a cooling medium, of a tank containing a liquid wherein said coil is immersed, said tank having an air passage surrounded by the coil, said coil having unequal portions at the respective sides of said air passage whereby an unbalanced cooling effect and a consequent thermo-siphon circulation is induced within said tank.

5. The combination with a coil for circulation of a cooling medium, of a tank containing a liquid wherein said coil is immersed, said coil having a major portion thereof at one side of the vertical axis of the tank, and the tank being formed with an air passage, the major portion of which is at the other side of the vertical axis of the tank, whereby the location of said coil and air-passage co-act to induce unbalanced temperature conditions and a consequent thermo-siphon circulation.

6. The combination with a coil for circulation of a cooling medium, of a tank containing a liquid wherein said coil is im-

mersed, said tank being formed with upper and lower air passages, the upper air passage being surrounded by said coil, and the coil having unequal portions at the respective sides of said passage, whereby unbalanced temperature conditions are induced in the upper portion of the tank, the lower air passage being eccentrically located relative to the vertical axis of the tank to form unequal columns at the respective sides thereof and induce corresponding unbalanced temperature conditions in the lower portion of the tank, a thermo-siphon circulation of the immersing liquid being effected by the unbalanced temperature conditions.

7. The combination with a container for a cooling medium, of a tank containing a liquid wherein said container is immersed, said tank being formed with an air passage eccentric to the vertical axis of the tank, whereby thermo-siphon circulation is induced around said air passage.

8. The combination with a container for a cooling medium, of a tank containing a liquid wherein said container is immersed, said container having unequal portions at opposite sides of the vertical axis of the tank, producing an unbalanced effect and a consequent thermo-siphon circulation.

9. The combination with a container for a cooling medium, of a tank containing a liquid wherein said container is immersed, said container having a major portion thereof at one side of the vertical axis of the tank, and the tank being formed with an air passage the major portion of which is at the other side of the vertical axis of the tank, whereby the location of said container and air passage co-act to induce unbalanced temperature conditions and a consequent thermo-siphon circulation.

In testimony whereof I sign this specification.

FRED J. HEIDEMAN.
